Owen, Owen & Compton

UNITED STATES PATENT OFFICE.

GEORGE H. LOBER, OF TOLEDO, OHIO, ASSIGNOR TO THE LOBER RADIATOR & MANUFACTURING COMPANY, OF TOLEDO, OHIO, A CORPORATION OF OHIO.

RADIATOR.

1,357,880.

Specification of Letters Patent. Patented Nov. 2, 1920.

Application filed January 30, 1919. Serial No. 274,064.

To all whom it may concern:

Be it known that I, GEORGE H. LOBER, a citizen of the United States, and a resident of Toledo, in the county of Lucas and State 5 of Ohio, have invented a certain new and useful Radiator; and I do hereby declare the following to be a full, clear, and exact description of the invention, such as will enable others skilled in the art to which it 10 appertains to make and use the same, reference being had to the accompanying drawings and to the characters of reference marked thereon, which form a part of this specification.

15 My invention has for its object to provide a radiator that will not be injured by repeated freezing. In the ordinary radiator, repeated freezing of the radiator causes permanent distention of the water passageways, 20 the passageways being enlarged each time the radiator is frozen causing, eventually, the radiator to burst. Each time that the water passageways are enlarged by freezing of the water it permits an increased 25 volume of water to reside in the passageways and subsequent freezing causes the further separation of the walls of the passageways until the radiator rips or bursts at the seams or at some weak point in the 30 radiator wall.

By my invention is provided a means whereby the volume of the water will be materially kept constant, notwithstanding repeated freezing of the water in the radiator. 35 In my invention is provided an elastic means which causes the return of the walls of the passageways to the same condition in which they existed before freezing. In this connection my invention particularly

40 relates to a means that forms a spacing means to allow the air to circulate between the air passageways and also a means for prevention of the permanent distention of the water passageways.

45 The invention may be contained in radiators of different forms and may be used to construct radiators of different forms. I have selected a radiator containing the invention and shall describe the same hereafter. The radiator selected is illustrated 50 in the accompanying drawings.

Figure 1 of the drawings illustrates a front view of a conventional form of a radiator and showing in a general and imperfect

way a radiator containing the invention. 55 Fig. 2 is an enlarged view of a part of a radiator core. Fig. 3 illustrates a broken perspective view of the parts of a radiator core to more clearly show the details of construction of the parts of the core. 60

1 is a radiator which has the ordinary water boxes at the top and bottom and the core 2 that connects the water boxes of the radiator. The core 2 has a plurality of pairs of strips having a width the same as 65 the thickness of the core. The pairs of strips form the walls of the water passageways which connect with the boxes of the radiator. Each pair of strips are spaced from adjoining pairs of strips to permit 70 the air passing between the pairs of strips to cool the water that passes through the passageways formed by the strips. The pairs of strips 3, 3 are provided with the channels 4 that are formed along the central portion of the strip and runs parallel with the passageway formed by the strips, that is, they run vertically with respect to the radiator. The edges of the strips are provided with zigzag corrugations 5 and the 75 channels 4 and the zigzag corrugations are so formed that when the pairs of strips are placed together such that the zigzag corrugations will fit one into the other, the channels 4 will be placed opposite to each other 80 in each pair of strips and so as to form enlarged portions 6 of the water passageways formed by the strips. The strips 3, 3 are formed of soft brass, that is, non-spring brass, in order that the strips may be readily 85 formed without ripping the brass. Other suitable metals may be used in lieu of the brass.

Between adjoining pairs of strips is located a strip formed of spring brass having, preferably, channels extending longitudinally with respect to the strips. The central portion of the strips 7 that form the spacing strips, are cut at intervals so as to form curved flanges 8 and 9 that extend 95 from the surface of the strip 7 and so as to present a curved surface to the strips that form the walls of the passageways located on opposite sides of the spacing strips 7. The central portion being of spring brass 100 and, if desired, the strips 7 may be thicker than the strips 3, the flanges 8 and 9 will operate as springs to press against the strips 105

3 to force the strips together until the portions of the strips 3, between the channels 4, abut. When the water in the passageways, formed by the pairs of strips 3, freezes it 5 causes distention or separation of the strips 3. When the ice melts the springs 8 and 9 operating on the walls 3 force them together and thus prevents permanent distention and increase of the volume of water, which, in 10 the subsequent freezing operation ordinarily would cause further distention than in the first freezing and would eventually result in the ripping or bursting of the radiator.

The spring flanges 8 and 9 are preferably 15 formed at points sufficiently remote to permit sufficient rigidity of the portions 10, located between the points at which the flanges 8 and 9 are formed, to cause the strips 3 to return to their normal position 20 after freezing. Inasmuch as the pressure required to cause the non-spring strips 3 to return, and in order that the effect of the temporary stretching, due to the freezing of the water, may be overcome, a considerable 25 pressure on the strips 3 is required. For this reason the portions of the strips 7 that are cut to form the flanges 8 and 9 may not be placed too near, otherwise there would be merely a tilting effect or a slight turning 30 movement of the spring flanges and the intermediate portions of the strips 7. Also to increase the rigidity of the spring flanges 8 and 9 and the intermediate portions 10 of the strips 7, the strips 7 may be provided 35 with vertical corrugations or with channels 11 of a form substantially the same as that formed in the strips 3, that is, substantially like the channels 4.

The spring flanges 8 and 9 are formed by 40 a die which will make two short cuts slightly remote from the edges of the strip and a transverse cut connecting the central portions of the longitudinal cut thereby leaving two lips that are bent by the die so that they 45 will curve outward and upward in one case, and curve outward and downward in the other case to form the spring flanges 8 and 9.

The strips 7 are also formed with zigzag 50 corrugations 12, similar in form to the zigzag corrugations 5 of the strips 3. In order that the zigzag corrugations may be formed in the strips 7, the edges of the strips 7 are annealed in such a way as to prevent the annealing of the central portion of the strip, 55 particularly that portion surrounding the cuts that are made in the strips 7 to form the spring flanges 8 and 9 which leaves throughout the length of the strips 7 a rigid band extending from the top to the bottom of 60 the strip while only the portions of the edges of the strips 7 are annealed that are bent or stretched in forming the zigzag edge corrugations 12.

In assembling parts of the radiator core 65 the strips 7 are so placed relative to the

strips 3 that the corners of the zigzag corrugations of the strips 7 will abut with the corners formed by fitting together the zigzag corrugations of the pairs of strips 3. This will form a space between consecutive 70 pairs of strips 3 through which the air may pass. The air will pass through the square openings that are formed by the placing of the strips having the zigzag corrugations together in the manner described. When the 75 strips are thus placed together they are secured in a form and dipped in melted metals, such as solder, so as to seal the water passageways formed by the pairs of strips 3 and to secure the strips 3 and 7 in their 80 relative positions and in such a position as to cause the spring flanges 8 and 9 to press against the walls of the passageways, that is, against the strips 3.

I claim:—

1. In a radiator, a plurality of pairs of strips having fitting corrugated sealed edges and forming passageways for water, a plurality of strips located intermediate the pairs of strips and having corrugated edges 90 for spacing the adjoining pair of strips and having flanges extending laterally from the central portions of the last named strips to press against the pairs of strips and located in opposite sides of the second named strips, 95 the said flanges formed by making a plurality of cross cuts located in spaced relation along the said second named strips and cuts extending parallel with and in proximity to the edges of the said second named strips 100 and bending the portions thus formed in opposite directions from the body portions of the second named strips by moving the edges formed by the transverse cuts in opposite directions from the second named strips. 105

2. In a radiator, a plurality of pairs of strips forming water passageways, a plurality of strips, the central portions of the strips formed of spring brass and having laterally extending spring flanges for pressing the pairs of the strips, the edge portions having corrugations for separating the pairs of strips. 110

3. In a radiator, a plurality of pairs of strips having fitting corrugated sealed edges 115 and forming water passageways, a plurality of strips, the edges of the second named strips having corrugations for separating the pairs of strips, the central portion of the second named strips formed of spring 120 brass and having laterally extending spring flanges for pressing together adjoining pairs of strips.

4. In a radiator, a plurality of pairs of strips forming water passageways, a plurality of strips having laterally extending spring flanges for pressing the pairs of strips and having channels extending through the flanges and the body of the strip. 125

5. In a radiator, a plurality of strips, the central portion of the strips formed of spring brass and having laterally extending spring flanges for pressing pairs of strips, the edge portions formed of annealed brass and having corrugations for pressing the pairs of strips.
6. In a radiator, a plurality of pairs of strips forming water passageways, the edges 10 of the pairs of strips having corrugations, a plurality of strips located intermediate the pairs of strips, the central portion of the last named strips formed of spring brass and having the laterally extending curved spring 15 flanges for pressing the adjoining pairs of strips and having annealed corrugated edges for spacing adjoining pairs of strips.
7. In a radiator, a plurality of pairs of strips forming water passageways, a plurality of strips located between the pairs 20 of strips, the central portions of the strips formed of spring brass and having laterally extending spring flanges for pressing the pairs of strips, the edge portions of the second named strips formed of annealed 25 brass and having corrugations for separating the pairs of strips.

In testimony whereof, I have hereunto signed my name to this specification.

GEORGE H. LOBER.
